UNITED STATES PATENT OFFICE.

JOHN P. BUCHHOLTZ, OF PHILADELPHIA, PENNSYLVANIA.

DESIGN FOR A LANTERN-BODY.

SPECIFICATION forming part of Design No. 21,518, dated May 3, 1892.

Application filed March 29, 1892. Serial No. 426,990. Term of patent 7 years.

To all whom it may concern:

Be it known that I, JOHN P. BUCHHOLTZ, a citizen of the United States, residing in the city and county of Philadelphia, State of Pennsylvania, have invented and produced a new and original Design for a Body of a Carriage Lantern or Lamp, of which the following is a specification, reference being had to the accompanying drawings, forming part thereof.

The leading feature of my design for a body of a carriage lantern or lamp is the many-sided sections thereof and a paneled neck between the sections.

Figure 1 represents a side view of a body of a lantern embodying my design. Fig. 2

represents a horizontal section thereof on line xx , Fig. 1.

In the drawings, A designates the body of the lantern, the same consisting of the upper and lower sections B and C, with a suitable frame therefor. Intermediate of the sections is a neck D, on which are panels E. The sections are many-sided.

I claim—

The design for a lantern-body, substantially as shown and described.

JOHN P. BUCHHOLTZ.
